UNITED STATES PATENT OFFICE.

JEAN PICOTIN, OF VILLEURBANNE, FRANCE.

WIRE-DRAWING MACHINE.

Application filed June 27, 1921. Serial No. 480,797.

To all whom it may concern:

Be it known that I, JEAN PICOTIN, citizen of the Republic of France, residing at Villeurbanne, Rhone, France, have invented 5 new and useful Improvements in Wire-Drawing Machines; and I do hereby declare the following to be a full, clear, and exact description of the same.

This invention relates to an improved 10 wire drawing process.

It is a well known fact that the passage 15 of a wire through a draw-plate produces heating, the intensity of which is proportional to the speed and deformation of the metal running through said draw-plate.

This increase of temperature is, in general, favorable to the working of the wire, as it renders the wire softer, and hence more ductile. The heating of the wire, however, 20 is not limited to its contact point with the draw-plate, but spreads along said wire, and accumulates chiefly at thin parts thereof and from which parts the heat is absorbed by the surrounding atmosphere. This heating 25 of the wire, followed by slow gradual cooling in the ambient temperature and around the winding reel, causes the structure of the wire to alter, and in some cases, according to the metals used, an actual allotropic transformation occurs. This pheomenon seems 30 to occur even in connection with copper, about 158° Fahrenheit. On the other hand, the wire, while cooling down on the winding reel contracts, thus undergoing considerable 35 tension.

The above described phenomena commonly result in reducing the lengthening and the speed with which the operation is effected and in producing a wire comparatively hard and brittle and unfit for any further drawing.

To avoid said disadvantages it has already been suggested to thoroughly dip both the draw-plate and the wire into a liquid bath. The wire is thus cooled down immediately after leaving the draw-plate but, as the wire had been cooled before entering said draw-plate, some of the advantages gained on the one hand are lost on the other.

The plant required for operating according to such a process is in general rather complicated. The immersion of the wire into the bath necessitates the immersion of the reels and of the wire drawing drums, 55 which causes the liquid to splash, limits the speed through the draw-plates and requires

the performing of the operation within water-tight vats.

Finally, it is quite impossible to use in connection with a plant as above mentioned, 60 a lubricant different from that of the refrigerating fluid; nor can withdrawing of the wire be facilitated by previously heating the wire as the latter is cooled in the bath before passing through the draw-plate. 65

It is therefore the object of this invention to provide a wire drawing process, wherein a cooling bath is arranged after each draw-plate for absorbing the heat produced on the passing of the wire through said draw-plate. 70

In the accompanying drawings:

Fig. 1 is a diagrammatical view of one embodiment of the invention wherein a plurality of draw-plates is provided, 75

Fig. 2 is a side elevation of a machine element of the so called "single end" type, permitting the working up of the process according to my invention, and

Fig. 3 is a vertical section thereof.

With particular reference to Figure 1, *a* is a receptacle fitted with a refrigerating fluid inlet tube *b* and with an overflow tube *c*; said receptacle *a* is provided, at the lower portion thereof, with an aperture *d*, permitting free passage of the wire. The wire to be drawn *e* passes upwardly through draw-plate, *f*, then through the refrigerating fluid. A drum *g* is provided on which the wire is wound, the wire being also wound on another drum *h* from where the wire is extended to the next draw-plate *f* fitted with a cooling device as hereinbefore described and through which the wire is drawn by drum *g*, and so forth, down to a last reel *g*, around which the finished wire is wound.

With particular reference to Figs. 2 and 3 wherein a practical form of the invention is shown, there is provided a metallic member 1 fixed on a table or bench 1' and forming a bearing for a horizontal shaft 2 mounted on bearings and revolved by a driving pulley 3; at both ends of said shaft are fixed two drums or winders 2' 2'', around which the wires are coiled, after having passed through the draw-plates 4, 4'. The pulley 3 is propelled by a belt the driven 100 bit of which is stretched out by a roller 5 mounted on a roller-holder 6, fitted with a handle 7. The holder 6 oscillates about a bearing 8 and is also capable of being moved 105

in a parallel direction with the shaft on said bearing.

When idle, the driven bit of the belt is set free and the springs 9 hold the roller-holder 5 tight against the driving pulley 3, which is thus kept motionless. When the handle 7 is actuated the roller 5 stretches the driven bit of the belt while a spur 10 carried by the inner surface of the arm of the holder remote from the pulley works on a helicoidal sloping surface in the adjacent face of the bearing 8 to displace the holder 6 in a longitudinal direction, thereby compressing the springs 9 and releasing the driving pulley 3 to permit the latter to revolve. The wires are now drawn vertically through the draw-plates by the winders 2' and 2''.

The member 1 is provided with a bearing 11 in the lower portion of which is supported a hollow bar 12 capable of being slid in opposite directions and connected with a supply of refrigerating fluid. Said bar is provided with apertures 13 forming outlets and through which the flow may be regulated by adjusting screws 14.

On said bar 12 are mounted draw-plate holders 15 which form tanks 16 with which the apertures 13 communicate to allow the filling thereof with the refrigerating fluid.

Members 17 fitted to stems 18 and secured by springs 19, keep the draw-plates 4, 4', in position to close the tanks 16. When previous heating of the wire is not required, the refrigerating fluid may be used to lubricate said wire upon its entering the draw-plate. The tanks 16 are held in place by the bar 12 by means of split portions integral with the tanks and clamped on said bar, also coiled wire-guides 20 secured to said stems 18 are provided for guiding the wire immediately after it has left the die-plate 16''.

The wire to be drawn, which may be coiled or wound up around a spool 21, is placed within a receptacle 22 containing a hot lubricating fluid. Said fluid enables a warmed up wire to enter the draw-plate if found useful, but also offers a most important advantage when the so called "all-in-a-file" system is adopted, said system being shown on the drawing, according to which the wire leaves by itself, under tractive power, the spool 21.

It is known that, when the aforesaid system is resorted to, the thread has a tendency to lock and that said locking causes the wire to break, upon the locked portion reaching the draw-plate.

When the wire is being unwound within a liquid, it is braked all the more when the height of the liquid is great and thus one may avoid the locking which occurs when the operation is performed without liquid, especially with wires of great diameter.

It will be obvious that the hereinbefore mentioned disadvantages are obviated and

that consequently, the results obtained by using the process according to the invention are as follows:

The wire is always heated by its passage through the draw-plate but, immediately after, it passes through a quantity of liquid which reduces its temperature, so that both heating and cooling of the wire take place within a very short time, and as a result the ductility of the wire is not diminished. 70 75

Another advantage is that the mechanical resistance of the wire before passing through the draw-plate is greater when the wire is cold than when it is hot, and said wire does not lengthen, after passing through the draw-plate, under the draught or tractive power of the drums g , g' . 80

A further advantage is that the wire, on leaving the receptacle a , carries a small portion of the refrigerating fluid with which it is surrounded upon reaching the drums g , h , g' , which permits the wire to slide very easily upon said drums, avoids abrasion, and reduces breakage to a strict minimum. 85

A further feature is that the wire, being in a cold state upon reaching drums g , g' , does not contract and, particularly, when wound up around the final reel, does not undergo undue strain and effort by reason of the gradual cooling of the wire on said reel, and the contraction resulting therefrom, and, 90 95

Finally, the process herein described permits the warming of the wire before passing the wire through the draw-plate, and covers the wire, if desired, with a lubricant 100 different from the refrigerating fluid.

Having thus fully described the invention what is claimed as new and desired to be secured by Letters Patent is:—

1. In a wire drawing machine, the combination with the draw-plate thereof, of a tank situated on the outlet face of the plate and containing a cooling medium for acting on the wire immediately subsequent to the drawing of the wire through the plate. 105 110

2. In a wire drawing machine in combination, a support, a hollow rotatable shaft operably mounted therein and serving as a conductor for a cooling medium and provided with a series of suitably spaced openings, draw-plate holders mounted on the shaft beneath the openings and forming tanks, draw-plates in the holders constituting the bottom of the tanks and through which wires are adapted to be drawn upwardly, and means 115 associated with the openings in the shaft for controlling the passage of the cooling medium from the shaft to the tanks.

In testimony whereof, I have signed my name to this specification in the presence of 120 125 two subscribing witnesses.

JEAN PICOTIN.
